UNITED STATES PATENT OFFICE

ELDER N. HATCHER, OF MANCHESTER, GEORGIA

PICKER-STICK PARALLEL MOTION

Application filed April 4, 1929. Serial No. 352,516.

This invention relates to picker stick parallel motions for looms and the general object of the present invention is to provide readily adjustable means whereby the tongue 5 engaging the edge of the picker stick and binding it in place may be shifted vertically either upward or downward to thus hold the picker stick in proper parallel.

A further object is to provide a device 10 of this character which may be used to adjust the picker stick.

A further object is to provide a parallel tongue picker stick which is so constructed as to cause the picker to throw the shuttle 15 straight and thus eliminate the shuttle wearing or splintering, thus preserving the life of the shuttle, lowering shuttle expenses and securing the better run of the warp, eliminating seconds and increasing production.

20 Other objects will appear in the course of the following description.

My invention is illustrated in the accompanying drawings, wherein I have illustrated a standard stand and picker stick shoe. 25 Figure 1 is a vertical sectional view of a parallel motion for picker sticks constructed in accordance with my invention.

Figure 2 is a longitudinal section enlarged on the line 2—2 of Figure 1;

30 Figure 3 is a fragmentary cross section enlarged on the line 3—3 of Figure 1.

Referring to these drawings, 10 designates the usual stand secured to the lay rock shaft 11. The upper face 12 of this stand 35 is formed to provide a rocker surface upon which the sole or rocker 13 of the shoe 14 is supported. The stand is provided with the usual tongue 15 which extends up through a slot 16 in the sole of the shoe. The picker stick 17 is disposed through an opening in the shoe and extends downward through an opening in the stand and is attached by means of the strap 18 to the spring 19 which, of course, tends to pull upon the strap so as to 40 move the picker stick to the position illustrated in Figure 1.

The shoe 14 is provided with the housing 20 which partially encloses the picker stick just above the sole of the shoe. A tongue 21 having flanges 22 embracing the picker

stick is supported in the housing 20 and engages the edge of the picker stick, the flanges 22 fitting over the sides of the stick and the flat face of the tongue engaging the edge of the stick. The tongue bears against the usual wedge-shaped bearing plug 23.

A picker stick bolt 24 passes through the housing 20 through a vertical slot in the tongue 21, through the picker stick and through a follower 25 which embraces the outer edge of the picker stick and bears against the flat face of the sole within the housing. The bolt, of course, carries a nut 26, the head of the bolt bearing against the outer face of the housing 20. So far I have described the ordinary or common construction.

By reference to Figure 1, it will be seen that the inner face 27 of the housing 20 is vertically curved inward from the point near the top of the housing to a point adjacent the sole 13 and that the tongue 21 has its face 28 confronting the face 27 also curved to conform to the curvature of the face 27. This face 28 is provided for a portion of its length with transversely extending rack teeth 29. The wall of the housing 20 is bored as at 30, this bore intersecting the inner face 27 of the housing wall and one end of this bore is screw-threaded as at 31. Extending through this bore is a shaft 32, one end of which is screw-threaded at 33 to engage the screw-threads 31, the other end of the shaft being provided with a many-sided head 34.

The shaft is provided with longitudinally extending gear teeth 35 so that the shaft in effect constitutes a gear wheel, the teeth of which engage the rack teeth 29. The screw-threaded end of the shaft is provided with a jam nut 36 whereby the shaft may be locked in any adjusted position.

It will be seen that with this construction by loosening the bolt 24 and, of course, loosening the jam nut 36, the shaft may be rotated by means of a wrench to shift the tongue 21 upward or downward and this upward or downward shifting of the tongue will cause not only the tongue to shift, but to bind upon the portion of the picker stick 95 below the bolt or the portion of the picker 100

stick above the bolt 24 and thus will cause the adjustment of the picker stick. This adjustment of the tongue effects its contact with the plug 23.

It is, of course, to be understood that the shoe 14 is formed, as it is on all looms, for the purpose of causing the picker carried on the picker stick to travel in a straight line parallel to the upper face of the lay beam or upper face of the shuttle box. It is necessary to adjust the picker stick so as to prevent the picker being too high at the point where it delivers the shuttle from the box to the face of the lay beam. This adjustment is secured in all forms of shoe now in use known to me by means of a tongue of the general character of the tongue 21 shown in my drawings. These tongues, however, are straight upon their inside faces as illustrated in the patent to Northrop 1,539,590 granted May 26, 1925.

In all other picker stick parallel motions known to me, as for instance in the Northrop parallel motion above referred to, if the picker on the end of the picker stick is too low, it is raised by screwing inward on a set screw bearing against the picker stick which lengthens the distance from the front end of the shoe 14 in my device to the picker on the picker stick. If the picker is too high with reference to the shuttle box, this set screw is not used and the only means of adjustment is to insert a leather wedge between the tongue and the stick at the lower end of the tongue which acts to shorten the distance from the front end of the shoe to the picker. Where a set screw is used for separating the tongue from the picker stick in order to raise the picker, and the bolt passing through the picker stick and the upward extension of the shoe is too tight, the tongue is very liable to break at the hole through which the bolt passes and the same is true when a leather wedge is used at the bottom. The tongue 21 of my structure is convex upon its inner face and confronts the concave face of the housing 20. Thus by raising the tongue 21 through the action of the toothed shaft 32 the upper portion of the stick is forced outward and by lowering the tongue the lower portion of the stick is forced outward and the upper portion inward so as to secure the desired distance of adjustment between the forward end of the rocker 13 and the pick when the latter is at the discharge end of the shuttle box. As far as I am aware, my construction is the only one which embodies a tongue which is adjustable up or down and which will secure the proper adjustment of the picker stick.

Another difficulty of the construction ordinarily used and which is present in the construction shown in the patent to Northrop 1,539,590 as heretofore referred to, is that the picker stick is very liable to work down.

This is because the tongue is a straight tongue

and the follower back of the stick does not fit down on the bed of the shoe. This, because of sudden jerks when in motion, lets the stick work down. Hence the pick gets out of parallelism with the bed of the shuttle box. The improved tongue 21, because of the fact that it has a convex face fitting against a concave face upon the housing 20 and because it is provided with notches engaging with the toothed shaft 32, cannot work down. The follower rests upon the bed of the shoe and obviously under these circumstances, there is no possibility of the tongue 21 working downward nor the stick 17 working downward. It is impossible for the stick to work upward. This is one of the main reasons why picker sticks get out of parallel. Of course, there are others such as the stick becoming warped or because the wedge 23 in the foot may wear.

Another difficulty with the ordinary parallel motion is that the picker stick and the picker are liable to jump up. This is for the reason that the lower end of the tongue ordinarily used is straight. The picker stick is moved with a quick jerk by means of the usual lug strap and when the stick comes in contact with the bumper at the delivery end of the shuttle box, it tends to cause the stick, the shoe and all connected parts to jump up. In my construction, however, the lower end of my parallel tongue is concave and is disposed close to the wedge in any position of the shoe so that it is practically impossible for the shoe and the picker stick with it to jump up.

In the Northrop Patent 1,539,590 to which I am referring merely to illustrate the disadvantages of the ordinary picker stick parallel motion, the tongue for a considerable distance below the wedge is straight and the tongue does not have a curved portion which bears at all times against the wedge. The jumping upward of the picker stick when the picker delivers the shuttle causes the shuttle to move irregularly in a more or less sinuous line hitting the side or top of the entrance at the other end of the loom, causing the shuttle to splinter and wear out just as badly as if the picker was out of parallel. My parallel tongue holds the shoe down on the bed of the stand at all times and particularly when the shoe is tilted over so that the end 13 comes in contact with the stand 12. Another advantage of my construction is that the tension on the usual check strap may be relieved to a point where this check strap is practically straight. The ordinary check strap has a tension adjustment at its middle and this strap catches or impedes the picker stick in the middle position of the picker stick so that when the shuttle strikes the picker, the strap eases the picker back to the outer end of its travel.

In my construction, the concave end of

the tongue 21 bears against the wedge 23 particularly where the picker stick is in its middle position and this frictional resistance of the pin 23 or wedge tends to cause the picker stick to ease back to the outer end of its travel. This permits the tension on the check strap to be relieved to an extent where the check strap will be practically straight so that there is no friction or wear on the check strap.

10 The check strap costs from forty to eighty cents and the life of a check strap is from one to three months and thus if with my construction the strap only lasts a month longer, 15 a plant having two thousand looms with two check straps to a loom will save a considerable amount.

It is to be particularly understood that my invention is applicable to all parallel tongues 20 on every make of loom as these parallel tongues in all makes of looms do the same work, and furthermore that it applies to all different sizes of shoe. I, therefore, wish to cover the application of my invention to all 25 parallel tongues and all looms and broadly speaking my invention particularly resides in the provision of a tongue and shoe in which the housing of the shoe and the face of the tongue are respectively concave and convex 30 and have a relatively close fit with relation to each other so that when the tongue is raised, the picker will be raised and by moving the tongue down, the picker will be lowered. This does not mean that the picker 35 stick is raised or lowered, but that the angle of this picker stick is changed so as to vary the distance between the shoe or rocker and the picker carried by the picker stick.

I claim:

40 1. A picker stick parallel motion including a stand, a picker stick, a shoe, a spring, a strap connected with the spring and with the picker stick and acting to return it to outward position, the shoe being provided with a housing, a tongue disposed between the housing and the picker stick, a bolt passing through the housing, through the tongue and through the picker stick, the tongue being longitudinally slotted to permit the passage of the bolt, 45 and means mounted on the housing and engaging the tongue for raising or lowering the tongue.

2. A picker stick parallel motion including 55 a stand, a picker stick, a shoe, a spring, a strap connected with the spring and with the picker stick and acting to return it to outward position, the shoe being provided with a housing, a tongue disposed between the housing and the picker stick, a bolt passing through the housing, through the tongue and through the picker stick, the tongue being longitudinally slotted to permit the passage of the bolt, 60 and means mounted on the housing for raising or lowering the tongue including a trans-

verse shaft having engaging gear teeth on the confronting face of the tongue.

3. A picker stick parallel motion including 70 a stand, a picker stick, a shoe, a strap and spring connected to the picker stick and tending to return it to outward position, the shoe being provided with a housing, a tongue between the picker stick and housing, the tongue being longitudinally slotted, a bolt passing through the housing, through said slot and through the picker stick, the wall of the housing confronting the tongue being concavely curved vertically and that face of the tongue confronting the housing wall being convexly curved vertically in conformity with the concave face of said wall, and means mounted on the wall whereby the tongue may be adjusted either upward or downward.

4. A picker stick parallel motion including 85 a stand, a picker stick, a shoe, a strap and spring connected to the picker stick and tending to return it to outward position, the shoe being provided with a housing, a tongue between the picker stick and housing, the tongue being longitudinally slotted, a bolt passing through the housing, through said slot and through the picker stick, the wall of the housing confronting the tongue being concavely curved vertically and that face 90 of the tongue confronting the housing wall being convexly curved vertically in conformity with the concave face of said wall, and means mounted on the wall whereby the tongue may be adjusted either upward or 95 downward including a shaft passing transversely through the wall and having gear teeth, the tongue having meshing gear teeth on its convex face, the shaft having means whereby it may be turned and held in adjusted position.

5. A picker stick parallel motion including 100 a stand, a picker stick, a shoe, a strap and spring connected to the picker stick and tending to return it to outward position, the shoe being provided with a housing, a tongue between the picker stick and housing, the tongue being longitudinally slotted, a bolt passing through the housing, through said slot and through the picker stick, the wall of the housing confronting the tongue being concavely curved vertically and that face of the tongue confronting the housing wall being convexly curved vertically in conformity with the concave face of said wall, 105 and means mounted on the wall whereby the tongue may be adjusted either upward or downward including a shaft passing transversely through the wall and having gear teeth, the tongue having meshing gear teeth on its convex face, one end of the shaft being screw-threaded and having screw-threaded engagement with the wall of the housing and with a jam nut, the other end of the shaft 110 having means whereby it may be rotated.

6. A picker stick parallel motion including a stand, a picker stick, a shoe through which the picker stick passes and having an upwardly projecting portion formed with a concave inner face, and a tongue disposed between this upwardly projecting portion and the picker stick, the tongue having an opening, a bolt passing through the picker stick and through the opening in the tongue and into the upwardly projecting portion, the upwardly projecting portion and the confronting face of the tongue being curved, the tongue being adjustable up or down with relation to the shoe.
- 15 7. A picker stick parallel motion including a stand, a picker stick, a shoe through which the picker stick passes, the shoe being provided with a housing, the inner face of the housing being concave, a tongue disposed between the housing and the picker stick and having a convex face disposed within the housing and fitting the concavity thereof, the tongue being slotted, a bolt passing through the picker stick through the slot of the tongue and into the housing, and means whereby the tongue may be vertically adjusted with reference to the housing.
- 15 8. A picker stick parallel motion including a stand, a picker stick, a shoe through which the picker stick passes, the shoe being provided with a housing, the inner face of the housing being concave, a tongue disposed between the housing and the picker stick and having a convex face disposed within the housing and fitting the concavity thereof, the tongue being slotted, a bolt passing through the picker stick through the slot of the tongue and into the housing, and means whereby the tongue may be vertically adjusted with reference to the housing, the tongue extending below the under face of the shoe and having its face remote from the picker stick concavely curved, and a bearing plug mounted in the stand and with the end of which the concave face of the tongue engages.
- 15 9. A picker stick parallel motion including a longitudinally slotted stand, a picker stick extending through the slot, a shoe rocking upon the stand and having a slot through which the picker stick extends, the shoe having an upwardly extending housing defining one wall of the slot, the inner face of the housing being concave, a tongue disposed between the picker stick and the housing and having a convex face confronting the concave face of the housing, the tongue being slotted, a bolt passing through the picker stick through the slot of the tongue and through the housing, means whereby the tongue may be vertically adjusted with relation to the housing and the picker stick and a plug projecting from one wall of the slot in the stand toward the picker stick and tongue, the tongue being extended downward through the slot of the stand and this extension having a concave face bearing against the end of the plug.
- 15 10. In a picker stick parallel motion, a shoe, a picker stick extending through the shoe, the shoe having an upwardly extending housing and a tongue disposed between the picker stick and the housing, the tongue having teeth and a toothed shaft being disposed in said housing, the teeth of which engage the teeth on the tongue whereby the tongue may be vertically adjusted.
- In testimony whereof I hereunto affix my signature.
